United States Patent Office

Des. 202,259
Patented Sept. 14, 1965

202,259

WARDROBE DOOR

Marron Kendrick, Atherton, Calif., assignor to
Schlage Lock Company

Filed July 14, 1964, Ser. No. 80,859

Term of patent 14 years

(Cl. D13—1)

FIG. 6

FIG. 5

FIG. 4

FIG-8

FIG-7

FIGURE 1 is a front elevation of the wardrobe door;
 FIGURE 2 is an elevation of one side of the same article;

FIGURE 3 is a cross section of the same article, the plane of section being indicated by the line 3—3 of FIGURE1;

FIGURE 4 is a rear elevation of the same article;

FIGURE 5 is an elevation of the other side of the same article;

FIGURE 6 is a top plan of the same article;

FIGURE 7 is a perspective view of the same article taken from the front and with the wardrobe closed;

FIGURE 8 is a perspective view of the same article taken from the front and with the wardrobe open;

FIGURE 9 is a perspective view of the same article taken from the rear and with the wardrobe closed; and

FIGURE 10 is a perspective view of the same article taken from the rear and with the wardrobe open.

The dotted lines shown in the several views are disclosed

I claim:
 The ornamental design for a wardrobe door, as shown and described.
